UNITED STATES PATENT OFFICE.

WILLIAM FORSTNER, OF IRVINGTON, NEW JERSEY, ASSIGNOR TO FORSTNER CHAIN CORPORATION, OF IRVINGTON, NEW JERSEY, A CORPORATION OF NEW JERSEY.

CHAIN.

Application filed December 15, 1926. Serial No. 154,929.

This invention relates to an improved construction of ornamental chain for personal wear; and has for its object to provide simple and effective means for adjoining the 5 links of the chain together without the use of solder.

A further object of the invention is to provide a construction of decorative chain, the links of which are of a desirable ornamental shape.

With these and other objects in view, the invention consists of certain novel features of construction, as will be more fully described, and particularly pointed out in the 15 appended claims.

In the accompanying drawings:

Figure 1 is a plan view of several connected links.

Figure 2 is a side elevation thereof.

20 Figure 3 is a detailed perspective view showing the body of one of the links.

Figure 4 is a perspective view of a blank for one of the connecting members.

25 Figure 5 is a perspective view showing the connecting member bent to substantially operating position.

Figure 6 is a perspective view of one of the constructions of links complete.

30 Figure 7 is a central sectional view of the same.

Figure 8 is a plan view of another different link of the chain.

35 Figure 9 is a central sectional view through several of the connected links showing the connected members before swaged into finished position.

Figure 10 is a modified construction of the links shown in Figures 6 and 7.

40 Figure 11 is a central sectional view of another modified form and Figure 12 is a central sectional view of a still further modified view of the link shown in Figures 6 and 7.

45 In the construction of ornamental chains for personal wear such as watch chains, key chains and the like, it is found desirable to provide a construction in which soldering is eliminated in order that the different colors of parts of the links of the chain may be used and not detrimentally affected and yet a construction in which the different links of the chain may be made in an ornamental shape to be attractive in appearance,

and in order to accomplish this, I have provided a chain of two different constructions 55 of links arranged with one construction alternating with the other throughout the chain; and the following is a detailed description of the present embodiment of this invention showing one arrangement of parts 60 by which the links of the chain may be formed to accomplish these desired results.

With reference to the drawings, 10 designates a link of one construction which is of bar form with openings or eyes 11 at 65 each of its ends which may be cut in the shape shown from sheet stock so as to be seamless.

A second construction of link which is designated 12 is so formed as to join the 70 links 10 together and alternate therewith throughout the series of links of the chain. This second construction comprises a body 13 having longitudinally disposed diametrically opposite grooves 14 on either side 75 thereof with an opening or recess 15 intermediate the ends of this bar and located in said grooves. A U-shaped member 16, which may be formed from a wire blank 17^a or cut out from sheet stock in the shape 80 shown in Figure 5, is passed through the opening 11 and positioned with its arms 17 lying in the grooves 14 of the body. The ends 18 of these arms are bent inwardly toward each other into the opening or recess 85 15 in the body as shown in Figure 9, after which the links are swaged in a swaging machine to close the arms 17 tightly against the body and in the grooves thereof, as illustrated in Figures 1, 2, 6 and 7 thus securely 90 joining the links of the chain together and preventing a separation thereof under ordinary longitudinal strains.

A variety of portions of the link 12 may be provided as illustrated in Figures 10, 11 95 and 12, in which openings 20 in the body 21 may be spaced apart, as illustrated in Figures 10 and 11, and the connecting members 22 may be of shorter formation and as illustrated in Figure 11 additional ornamental pieces 23 may be attached, or if desired a fancy shape of connector member 24 may be associated with the body member 13, as illustrated in Figure 12.

It will also be apparent that an opening 100 or recess 15 or 20, need not necessarily ex-

tend entirely through the body but may only be of sufficient depth on either side to receive the inturned ends such as at 18 of the connecting members.

5 From the foregoing, it will be seen that I have provided a simple construction or ornamental chain in which the parts of alternating links are duplicates one of the other thus providing a chain which may be 10 made in quantities at a minimum cost and yet one in which different parts of different colored gold and these different colors be unaffected in attaching the same together as the necessity of the use of solder or heat 15 is eliminated.

The foregoing description is directed solely towards the construction illustrated, but I desire it to be understood that I reserve the privilege of resorting to all the 20 mechanical changes to which the device is susceptible, the invention being defined and limited only by the terms of the appended claims.

I claim:

25 1. In an ornamental chain, a link member having a body, a recess therein intermediate

its ends, and two U-shaped connecting members extending along said body and engaging the sides thereof, and having connecting portions extending into said recess and 30 center loop portions extending beyond the body to form connecting loops for interconnection with adjacent chain links.

2. An ornamental chain comprising links of two different constructions alternately 35 arranged in connected series one construction of link being of bar form with spaced openings one adjacent each end, the other of said constructions comprising a body having diametrically oppositely disposed 40 grooves extending longitudinally thereof with an opening therethrough connecting said grooves, oppositely disposed U-shaped members having their arms in said grooves and extending through the end opening of 45 the adjacent bar links, the ends of the arms of said members extending toward each other into the opening in said body to lock the parts together and the links against separation. 50

In testimony whereof I affix my signature.
WILLIAM FORSTNER.
